Aaron Steaman
Letter Patent

The Schedule referred to in these Letters Patent annexed part of
the same containing a description in the words of the ^{said} Aaron Steaman
himself of his improvement in a Machine for making Bedsteads

To all to whom these presents shall come, Aaron Steaman of the town of
Pittsford in the County of Monroe and State of New York sends greeting. Be it
known that I the said Aaron Steaman have invented constructed and
applied to use new & useful improvements in machine for making bed-
steads called by me "a bedstead machine" and that the following is a
full & exact description of the construction & operation of the said machine
as mounted or improved by me. The said machine is composed of two
parts the one for cutting the screws in the side & end rails of the bedstead
and the other for cutting the holes or nuts in the posts of the bedsteads to re-
ceive the said screws. That part of the said machine for cutting the screws
is composed of two upright standards called a head block and heel block
about ten inches high, which may be fastened to a plank or piece of timber
on a common work bench with holes or grooves at suitable distances so
as to admit the side or end rails of bedsteads of different lengths. From the
said upright standards and near the upper end are two screws one on
each standard projecting towards each other with a centre pin in each
the one a right hand and the other a left hand screw. To each screw is at-
tached a screw tool with handles. Each screw tool including the handles
is about eleven inches long. Each screw tool is equally fitted to the screw
and so constructed as to commence cutting the screw a trach end of the rail
at the same point. Upon the inner side of each screw tool is a thin cap to
regulate the cutting of the screw describing about five eights of a circle and
even with the V or cutter which cap may be made of wood or any kind of
metal and one eighth of an inch thick or thicker or thinner. Upon the outside
of each screw tool is another cap to keep the screw tool from rattling which
may be one inch thick or more. One of the standards or blocks is made move-
able

6004 X

able by means of a screw or otherwise in order to let in the rails between the centre pins and to fasten the ends thereof. Between the two upright stand rods or head block & heel block is a vice to hold the rails from turning when cutting the screws. That part of the machine for cutting the boxes or nuts in the posts to receive the screws is composed of two screw augers, a right hand and a left hand auger which may be made of steel or cast iron. When made of cast iron a steel cutter is dovetailed into each auger. Accompanying each auger is a box or plate with a ledge on the left hand side of the right hand auger and on the right hand side of the left hand auger to keep the post in its proper position while cutting the boxes or nuts. The boxes or plates serve as guides to the augers and must be so made as to cause each auger to commence cutting at the same point. The specific new and useful improvements herein before described and claimed by me as the inventor are the following: First the cast iron augers with the cutters dovetailed into the same. Second the boxes or plates accompanying the augers. Third the caps upon the screw tools to regulate the cutting of the screw. Fourth the standards or head block and heel block with the screws attached to the same. By means of these improvements the screw in the ends of the rails and the nuts or boxes in the posts are always cut uniform so that the board will in all cases come together with close joints.
